UNITED STATES PATENT OFFICE

2,558,437

ILLUMINATING ATTACHMENT FOR
TELEPHONES

George Hronec, Lorain, Ohio

Application March 14, 1950, Serial No. 149,638

3 Claims. (Cl. 179—90)

1

The present invention relates to new and useful improvements in illuminating attachments for telephones to illuminate the dial as well as the receiver of the telephone.

An important object of the invention is to provide a novel housing for a lamp mounted on a telephone base in front of the dial to shield the lamp and to project a beam of light onto the dial and receiver whereby the lamp may serve as a night light.

Another object is to provide an illuminating attachment which is connected directly to the current for operating the telephone to eliminate exposed wires such as are usually plugged into a house circuit.

A further object is to provide a device of this character of simple and practical construction, which is neat and attractive in appearance, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view showing the illuminating attachment in position on a telephone and with parts shown in section;

Figure 2 is an enlarged sectional view taken on a line 2—2 of Figure 1;

Figure 3 is a sectional view taken on a line 3—3 of Figure 2;

Figure 4 is an enlarged plan view of the base of one of the lamp housings;

Figure 5 is an enlarged fragmentary group perspective view showing the connecting means between the outer end of the cover for the housing and the base;

Figure 6 is an enlarged group perspective view of the connecting means for the front of the cover;

Figure 7 is an enlarged perspective view of the lamp shield; and

Figure 8 is a diagram of the electric circuit for the lamp and switch.

Referring now to the drawings in detail, wherein for the purpose of illustration I have disclosed a preferred embodiment of my invention, the numerals 5 and 6 designate a pair of lamp units or housings generally, each including an elongated base 7 having one end 8 of reduced width and having an upstanding flange 9 at its other

end provided with a pair of outwardly projecting pins 10.

A cover 11 is snugly fitted over the base 7 and has an open reduced end 12 at the inner end of the cover which abuts the inner open end of the adjacent cover to close the inner open ends of the covers one against the other. The outer end of cover 11 is formed with a pair of recesses or holes 13 to lockably receive the pins 10 and the front of the cover adjacent its inner end is formed with an internal loop or eye 14 engaged by an upstanding locking tongue 15 on the front edge of base 7.

The rear of cover 11 is provided with a window 16 of cellophane or other suitable material and behind which is mounted a lamp 17 in a bracket or clip 18 attached to base 7. A reflector 19 is placed over lamp 17 and is held in position by dowels 20 rising from the base and received in openings 21 in the lower edge of the shield.

The base 7 of each unit is secured by suitable fasteners 22 to the base 23 of a dial telephone 24 immediately in front of the dial 25 and with the inner ends of the units abutting to close the inner ends of the covers 11.

The lamps of both units 5 and 6 are connected to the telephone circuit by wires 26 passing through an opening 27 in one of the base members 7 into the base of the telephone and a switch 28 is connected to the lamps and mounted on top of one of the units.

The lamp units are placed end to end on the telephone base, as shown in Figure 1, and the wires for the lamps of the two units pass through the open abutting ends. The light from the lamps is projected toward the dial 25 and is sufficient to also illuminate the receiver of the telephone so that the entire telephone may be adequately illuminated.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. An illuminating attachment for telephones adapted to be secured to the top of the base

of a telephone comprising a lamp housing including a base having an upstanding flange at one end, a dowel pin projecting outwardly from the flange, a cover forming part of the housing and fitted over the base, said cover having a recess receiving the pin, an internal loop adjacent the other end of the cover, an upstanding tongue on the base of the housing engaged in said loop to lock the cover to the base of the housing, a window in one side of the cover, a lamp in the housing behind the window for directing light rays through the window, means supported on the base holding the lamp behind the window, and means for mounting the attachment on the base of a telephone.

2. An illuminating attachment for telephones adapted to be secured to the top of the base of a telephone comprising a lamp housing including a base having an upstanding flange at one end, a dowel pin projecting outwardly from the flange, a cover forming part of the housing and fitted over the base, said cover having a recess receiving a pin, an internal loop adjacent the other end of the cover, an upstanding tongue on the base of the housing engaged in said loop to lock the cover to the base of the housing, a window in one side of the cover, a lamp in the housing behind the window and connected to a circuit in the telephone base, a reflector for the lamp, a switch for the lamp mounted on the cover, means carried by the base supporting the lamp behind the window and in the reflector, and

means for mounting the attachment on the base of the telephone.

3. In a telephone including a base and a dial on top of the base, a device for illuminating the dial comprising a base plate secured to the top of the base adjacent the dial, said plate including an upstanding flange at one end, a cover fitted over the plate and having an opening therein facing the dial, interfitting fastening means between the flange and one end of the cover for retaining the cover positioned over the plate, a lamp holding bracket secured to the base, a lamp carried by the bracket and supported in registry with the opening to direct light rays toward the dial, means operatively connecting the lamp to a source of electric current, and additional interfitting fastening means between the other end of the cover and the plate retaining the cover relative to the plate and over the lamp and the lamp holding bracket.

GEORGE HRONEC.
